against the journal to be lubricated at all times. Variations in the thickness of the several applicators will not cause variation in the contact between the rounded surfaces and the journal.

The action of the springs 24 will hold the felts against the journal and at the same time hold the studs 26 in the holes 25, so that the applicators are maintained in proper position and on their respective carriers. However, when it is desired to remove an applicator, the springs 24 for an applicator may be compressed enough to enable the operator to remove the stud 26 from the hole 25 and lift the applicator out of place. Correspondingly, new applicators can be readily inserted.

In the form shown in Figs. 12, 13, and 14, the base 50 has flanges 51 at the upper end, which receive a hinge pintle 52 for three sets of links or levers 53, each having one end pivoted on the hinge pintle 52 and the opposite upturned end pivoted on a pintle 54 to one of the carriers or supporting members 55, 56, and 57. The carriers have parallel flanges 58 receiving the pintles 54, to which they are riveted.

The outer flanges 58 of the carriers 55 and 57 are formed by striking out a portion of the carrier, as indicated at 60 (Fig. 13).

Each carrier is urged away from the base by two helical springs 61 having their ends surrounding guides or studs 62 on the base and the carrier.

The hinge relation between the arms or levers 53 and the base and the carriers permits each of the carriers to have individual freedom to rock about the pintles 54 and to move toward and away from the base 50. Hence, they can adjust themselves to the journal substantially as disclosed in connection with the form shown in Figs. 1-11.

The applicators for the form shown in Figs. 12-14 correspond to those shown in Figs. 1 and 2, and are made fast by the same sort of studs and holes.

I claim:

1. In a lubricator, a base, a plurality of supporting members alongside each other on the base, means pivotally mounting said supporting members pivotally on the base with individual freedom to rock and to resiliently yield to pressure toward the base, a felt holder carried by each supporting member, a felt body retained in said holder and having a journal contact surface projecting from the holder, said supporting member and said felt holder having contacting surfaces and one of said surfaces having a stud projecting therefrom engaged within an opening

4

in the other surface to retain the felt holder in position on the supporting member.

2. In a lubricator, a base, a plurality of supporting members alongside each other on the base, each having an opening, means mounting said supporting members pivotally on the base with individual freedom to rock and to resiliently yield to pressure toward the base, a felt holder carried by each supporting member having a stud received in the corresponding opening, and a felt body retained in each of said holders and having a journal contact surface projecting from the holder.

3. In a lubricator, a base, supporting members alongside each other on the base, hinge means pivotally connecting the base and the supporting members with limited freedom to move bodily straight apart and with the supporting members free to swing relatively to the base, resilient means urging them bodily straight apart, a felt holder demountable on each supporting member, and a felt body retained in said holder and having a journal contact surface projecting from the holder.

4. In a lubricator, a base, supporting members alongside each other on the base, hinge means pivotally connecting the base and supporting members with limited freedom to move bodily straight apart, resilient means urging them bodily straight apart, a felt holder demountable on each supporting member, and a felt body retained in each holder and having a journal contacting arcuate surface projecting from the holder, the several surfaces being radially aligned.

5. In a lubricator, a base, a supporting member, an intermediate member hinged to the base, means connecting the supporting member and the intermediate member for limited freedom to move apart from the base, resilient means reacting directly between the base and supporting member for urging them apart, a felt holder demountable on the supporting member, and a felt body retained in the holder and having a journal contact surface projecting from the holder.
